WING SLOT ARRANGEMENT

Garland P. Peed, Jr., Pacific Palisades, and Thorvald K. Petersen, Santa Monica, Calif., assignors to Douglas Aircraft Company, Inc., a corporation of Delaware

Application September 25, 1940, Serial No. 358,218

12 Claims. (Cl. 244—42)

This invention relates broadly to wing slots for aircraft and more particularly to slotted lift modification devices and improved closure means therefor.

In the use of slot creating devices in wings for increasing their lift characteristics and for delaying stall conditions, the entrance or mouth of the slot usually presents an undesirable drag in the normal or aligned attitude of the wing, or its adjacent slot forming elements. This applies to slots which are either of the fixed type entirely within the main airfoil, and the drag results are considerably more noticeable in the variable lift type between the main airfoil and a movable auxiliary airfoil, such as an aileron, or flap at the trailing edge, or a vane at the leading edge of the main airfoil. In the more generally used form these slots are disposed laterally, or spanwise of the wing, and present a wide mouth or entrance at the lower surface which reduces gradually as it slopes upwardly and rearwardly to a relatively narrow exit on the upper surface at which the air induced by the open slot is directed rearwardly in the line of the airflow adjacent to the upper wing surface.

Generally speaking, the use of slot closures, or doors, is well known in the art and various modifications have been suggested and used whereby the closures have been carried by either the fixed airfoil or the movable auxiliary airfoil and have been either automatically, or separately, arranged to close the slot in the high-speed low-drag attitude of the wing. The present improvement is, however, directed to a novel arrangement of retractable closure elements which has been found to eliminate a number of the difficulties presented by the prior devices and has attained improved results both in operation and performance of the wing and its high lift characteristics.

It is accordingly an object of the present invention to provide slot closure doors which substantially fully close the mouth of the slot in the normal or aligned attitude of the wing elements. It is a further object to provide slot closure doors presenting a dissimilar configuration of their upper and lower sides and articulated such that they are folded together or retracted into a relatively compact space.

A further object of the present invention contemplates a novel linkage arrangement for bodily moving the interconnected closure elements between its extended slot sealing position and its retracted or stowed position. It is a further object to provide a parallelogram linkage for such

an actuating mechanism which insures the proper positioning of the component parts of the closure in both of its extreme positions. A still further object embraces the provision of such a device in which a face of one of the closure elements forms a portion of the wing lower surface in its extended position and the opposed face of the closure element forms a portion of the desired contour of the forward wall of the slot in its retracted position.

Other objects and advantages of the present invention will become apparent to one skilled in the art after a reading of the following description taken together with the accompanying drawing.

The single figure is a cross sectional view of a preferred modification of the present invention applied to a slotted flap showing the closure means in both its extended and retracted positions and the flap in its aligned and downwardly extending positions.

In the figure the numeral 1 indicates the trailing portion of an airfoil of the desired cross-section, the trailing edge of which forms the forward and upward contour of the slot which extends from the region of the leading portion of its mouth at 26 and extends upwardly and rearwardly with respect to the wing to its trailing portion 1a which terminates at the closed slot exit at 28. The numeral 2 indicates a trailing edge flap which may be hinged or otherwise supported from the main airfoil 1 and provided with suitable control mechanism, not shown, which permits the flap to be extended rearwardly and downwardly into a high-lift slot-forming attitude indicated by the dotted lines. The leading edge of the flap 2a is formed with the desired contour or profile such that as the flap is extended rearwardly and downwardly it forms the rear wall or boundary of the slot and determines its desired shape for deriving the optimum slot effect at any given position of the flap.

While the preferred embodiment of the present invention has been applied to a slot formed between the wing and its trailing edge flap it is set forth that the present invention is also applicable to slotted ailerons, and to slots provided entirely within the fixed portion of the wing; and that its application thereto with the necessary modifications will be apparent to those skilled in the art.

The closure elements comprise the forward triangular shaped member 4 and the rearward member 5 of generally similar cross section which

are interconnected by the link 6. The latter is pivoted at its upper terminal adjacent the upward forward corner of the rear element 5 by means of the pivotal connection 7, and is pivoted to the forward element 4 at the pivot 8 adjacent the lower surface of the forward closure element. The elements 4 and 5 in their extended or full line position form a substantially complete closure for the mouth of the slot extending from the clearance space 26 adjacent the main wing 1 to the similar space 27 adjacent the flap in its up or aligned position. The closure elements are disposed such that their portions of greatest depth adjoin or closely oppose each other and their acute edges extend outwardly and oppositely toward the spaces 26 and 27. A second link 9 is pivoted to the upper portion of the element 4 at the pivot 10, and to the lower portion of the element 5 at pivot 11. It is also provided with an offset or bellcrank portion 12 which is pivoted to a third link 13 by means of the pivot 14. The opposite terminal of the link 13 extends forwardly and is provided with a fixed pivot 15 carried by the main wing section.

The fourth link 16 is pivoted to the forward portion of the element 4 by means of the pivot 17 and is also pivotally mounted at 18 upon the wing. Another, or fifth link 19 also pivotally carried at 20 upon the fixed wing 1, is pivoted at its outer extremity to the forward closure element 4 at the pivot 10 at the intermediate portion of the arms of the link 9-10. The third link 13 is also provided with a lug portion 25 to which is pivotally connected at 22, the piston or movable element 21 of an actuating device 3, the cylinder portion of which is pivotally carried upon the fixed wing 1 at the pivot 24. The trailing edge of the main wing section forming the front contour of the slot is provided with an opening 23 through its exterior surface and an adjoining interior space is provided for the retraction or storing of the folded closure elements as indicated by the dotted lines in the figure.

The extended position of the closure elements 4 and 5 as indicated by the full lines represent its normally closed attitude in which the flap 2 is in its upper position aligned with the wing for cruising, or high speed flight conditions. Assuming now that it is desired to extend the flap 2 into its high lift slot forming position indicated by the dotted lines, fluid pressure is fed into the lower portion of the actuating cylinder 3 beneath the piston whereby the piston rod 21 is caused to move upwardly for the folding and retraction of the closure assembly. A fluid actuating cylinder has been selected for the preferred modification which may be caused to operate simultaneously by suitable well known interconnection with the flap operating mechanism, but other suitable actuating devices, such as mechanical or cable operating means may be substituted for that shown. As the piston rod 21 moves upwardly the link 13 through its pivotal connection 14 with the arm 12, lifts the closure assembly 4-5 upwardly through the opening 23 in the slot wall into its retracted or dotted position. The link 19 forming a parallelogram arrangement with the link 13 and being of substantially the same length continues upwardly in a continual parallel relationship and fixedly determines the positions of the pivot pins 10 and 11 of the closure elements 4 and 5 respectively.

As the linked or articulated closure elements are lifted bodily into the retracted position the

interconnecting link 6 is caused to conform with the positions of the pivots 10 and 11 which have been determined by the interconnecting link 9, and assisted by the overhanging weight of the rear element 5 the latter is caused to rotate in a clockwise direction in which the links 6 and 9, which were formerly crossed, are caused to be uncrossed or substantially separated. At the same time, the link 16 by virtue of its pivotal connection toward the forward portion of the element 4 tends to maintain its forward or acutely angled portion in a forward and downwardly extending attitude serving to define the retracted position of the forward element. The element 5 having its pivot portions 7 and 11 now definitely positioned with respect to the link 4, is caused to assume an adjacent position in which the former downwardly facing undersurface portions of the closure elements are now brought together and substantially meet. In this retracted position of the element 5, its former upwardly facing surface 5a has been rotated with the element to a position where it now substantially fills the opening 23 and forms part of the forward wall of the slot, and is aligned and continuous with the slot wall.

It will be noted that as the piston rod 21 is withdrawn or telescoped within the cylinder 3 the entire piston-cylinder assembly rotates in a clockwise direction about its trunnion, or pivot, 24 following the path of the pivot 25 into the retracted position of the link 13. In the retracted position of the closure elements 4 and 5 and the extended dotted position of the flap 2 a fully unobstructed slot is presented in which its forward wall has been given the desired optimum profile in which the portion occupied by the sloping face 5a of the element 5 is not dependent upon the form of the lower flat face of this element. In other words, the lower nearby surface of the wing and the lower surface of the closure elements is usually a flat plane surface whereas in certain slot shapes the wall extending between the edges of the opening 23 might preferably be curved. This desired curve can readily be accomplished by suitably shaping the upper surface 5a of the rear closure element, inasmuch as the flat surface of the element has been retracted into the interior position and is no longer presented to the airflow through the slot. In the closed position of the slot the elements 4 and 5 are aligned to form a wide base triangle of relatively large chordwise dimension, and in the retracted position they are compacted or substantially superimposed. By compacting or folding the closure elements together as they are retracted an opening of but one half the usual length is required to be provided in the wing trailing edge and more readily adapts itself to the desired slot contour. Other advantages and uses of the present invention which will become apparent to those skilled in the art are intended to be embraced within the spirit and scope of this invention as more definitely set forth by the appended claims.

We claim:

1. In aircraft construction, a main airfoil, a trailing edge flap associated with said airfoil in slot forming relationship, the trailing portion of said airfoil forming a wall of said slot, an opening in said wall, a closure comprising a plurality of articulated sections supported from said airfoil, and actuating means for bodily moving and compacting said closure from its extended slot-closing position underlying the leading edge of

said flap through said wall opening to a retracted position within the main airfoil.

2. In a wing system including a slot, a pair of closure elements for closing the mouth of said slot, said elements being interconnected by a pair of links crossed with respect to each other in the slot-closing attitude, an actuating linkage pivotally carried by said wing and pivotally connecting one of said links adapted for the bodily retraction of said elements into said wing and means joining said linkage with one of the first said links whereby said closure elements are brought compactly together as they are bodily retracted.

3. In a wing system, a relatively fixed airfoil, a movable auxiliary airfoil normally aligned with the trailing edge of said fixed airfoil and adapted to form a through slot therebetween in its extended attitude, means for closing the entrance of said slot in the aligned position of said auxiliary airfoil comprising a pair of articulated elements movably supported from said fixed airfoil by parallel links and actuating means for simultaneously compacting and retracting said elements into said fixed airfoil.

4. In a wing system, a relatively fixed airfoil, an auxiliary airfoil normally aligned with the trailing edge of said fixed airfoil and adapted to form a slot therebetween in its extended attitude, means for closing the entrance of said slot in the aligned position of said auxiliary airfoil comprising a pair of articulated elements movably supported from said fixed airfoil by parallel links, and actuating means for simultaneously compacting and retracting said elements into said fixed airfoil, the said closure means comprising a pair of elements interconnected by a pair of links whereby the elements are folded together as they are retracted.

5. In an aircraft wing, a main airfoil, a flap movably associated therewith in slot-forming relationship, a slot closing arrangement comprising a pair of foldable closure elements pivotally interconnected by a pair of links, one of said links having an offset apertured portion, actuating means pivotally engaging said aperture for bodily moving said elements between the extended slot-closing position underlying said airfoil and flap and its retracted folded position within said wing, the other link of said pair adapted to limit relative movement of one element with respect to the other as both are moved bodily.

6. In an aircraft wing, a main airfoil, a flap movably associated therewith in slot-forming relationship, a slot closing arrangement comprising a pair of foldable closure elements pivotally interconnected by a pair of links, one of said links having an offset apertured portion, actuating means pivotally engaging said aperture for bodily moving said elements between the extended slot-closing position underlying said airfoil and flap and its retracted folded position within said wing, the other link of said pair adapted to limit relative movement of one element with respect to the other as both are moved bodily, and pivotal connections between one of said elements and said airfoil adapted to definitely position said element with respect to the wing in the said extreme positions.

7. In an aircraft wing system, a slot-closing arrangement comprising a pair of foldable closure elements pivotally interconnected by a pair of links, one of said links having an offset extension forming a bell-crank, a pair of substantially parallel actuating links pivotally carried by said

wing and connected to spaced pivots on said offset extension, a positioning link pivoted to said airfoil and to one of said closure elements, and means to actuate said parallel links whereby as the closure elements are retracted bodily from their slot-closing position into their stowed position within the wing, one of said elements is guided by said positioning link and the second said element is rotated with respect thereto by the joint cooperation of said first pair of interconnecting links, such that said closure elements are foldably compacted against each other.

8. In an aircraft wing, a slot-closing system comprising dual foldable closure elements, means pivotally interconnecting said elements and including an angular shaped link, actuating means for moving said elements between their unfolded slot-closing and folded slot-opening positions, and means to impart rotation to one of said elements with respect to said angular link during retraction into the wing whereby said interconnecting means imparts rotation to the other of said elements in an opposite direction, to compactly fold said elements together.

9. In a slot-closing system for an aircraft wing, in combination, a pair of bodily movable slot-closing doors, a link member pivotally interconnecting said doors having a third pivotal connection, parallel actuating linkage pivotally engaging said link member at two of its said pivots adapted to bodily move said doors between extended slot-closing and retracted slot-opening positions while maintaining said link member in parallel relationship with said wing, and further linkage means initiated by said actuating linkage adapted to rotate said doors in opposite directions to a compactly folded relationship in the retracted position within the wing.

10. In a slot-closing system for an aircraft wing having a trailing flap, a slot between said wing and said flap having an opening in a wall thereof, a pair of foldable closure elements adapted in extended position to underlie said wing and flap and to close said slot, a closure-carrying member pivotally supporting said elements at spaced points, actuating means pivotally associated with said member adapted for its movement between extended and retracted positions, means pivotally interconnecting said wing with one of said elements, and further means pivotally interconnecting said elements with each other at points other than the first said points, whereby in the extended position of said closure assembly the mouth of said slot is substantially closed and retraction of said assembly imparts movement of said closure elements with respect to each other and to said wing to a compactly folded position in which the assembly occupies said slot wall opening and in which a surface of one of said elements completes the contour of the said wall of the opened slot.

11. In a wing having a profile comprised of normally aligned forward and trailing portions disposed for the formation of an aerodynamic slot therebetween, a foldable closure supported from one of said wing portions adapted to be simultaneously extended and unfolded to underlie both said forward and trailing portions in alignment with the undersurface profile of said portions, said closure also adapted to close said slot in said extended position in which it forms a part of said wing profile, and actuating means to simultaneously fold and compact said closure in retracting it to a slot-wall-forming position within said forward wing portion.

12. In a wing having an exterior profile comprised of a forward and a trailing portion, said wing portions being disposed for the formation of a slot extending between the lower and upper opposed surfaces of said exterior profile, a closure comprising a plurality of foldably articulated sections supported from one of said wing portions adapted to be extended to underlie both said wing portions and to close said slot in said ex-

tended position in which it forms an aligned part of said exterior profile, and actuating means to simultaneously fold and compact said closure in retracting it from said extended position to a position within said wing in which it forms no part of the exterior profile of said slotted wing.
